UNITED STATES PATENT OFFICE.

CHARLES D. FAGAN, OF SHARON, PENNSYLVANIA, ASSIGNOR TO SHARPSVILLE BOILER WORKS, OF SHARPSVILLE, PENNSYLVANIA, A CORPORATION OF PENNSYLVANIA.

DESIGN FOR A DIAL FRAME.

Application filed July 5, 1927. Serial No. 22,663. Term of patent 14 years.

To all whom it may concern:

Be it known that I, CHARLES D. FAGAN, a citizen of the United States, residing at Sharon, in the county of Mercer, State of Pennsylvania, have invented a new, original, and ornamental Design for a Dial Frame, of which the following is a specification, reference being had to the accompanying drawings, forming a part thereof.

Fig. 1 is a front elevational view of the invention.

Fig. 2 is a side elevational view of the invention.

Fig. 3 is a top plan view of the invention.

The design comprising the present invention is intended more specially as a frame for dials for meters such as are used in automobile gasoline service stations.

I claim:

The ornamental design for a dial frame, substantially as shown and described.

CHAS. D. FAGAN.
